UNITED STATES PATENT OFFICE.

FRANK H. SEBRING, JR., OF SALEM, OHIO.

COATING DEVICE.

1,326,979.

Specification of Letters Patent.

Patented Jan. 6, 1920.

Application filed August 21, 1919. Serial No. 318,871.

To all whom it may concern:

Be it known that I, FRANK H. SEBRING, Jr., a citizen of the United States, residing at Salem, in the county of Columbiana and 5 State of Ohio, have invented a new and useful Coating Device, of which the following is a specification.

The invention relates to coating devices and has more especial reference to a device 10 of this character designed to coat china or porcelain plates and similarly shaped articles with the liquid coating of glaze which is ordinarily applied to such articles.

The objects of the invention are to provide 15 a device which automatically coats the plates or other articles, removes the excess liquid coating therefrom and delivers the coated articles from the machine.

Further objects are to provide a device 20 of this general character comprising a tank containing the liquid coating, an oppositely inclined track leading through the trough, a drum within which the articles to be coated are placed and means for moving 25 said drum over said track and delivering it from the tank.

With these objects in view the invention consists in the novel construction and arrangement of parts, hereinafter described, 30 illustrated in the accompanying drawings, and particularly pointed out in the appended claims, it being understood that various changes in the form, proportions, size and minor details of construction may be made 35 within the scope of the appended claims, without departing from the spirit or sacrificing any of the advantages of the invention.

The invention thus set forth in general terms is illustrated in the accompanying 40 drawings forming part hereof, in which—

Figure 1 is a longitudinal sectional view of the device;

Fig. 2, a plan view of the same;

Fig. 3, a section taken on the line 3—3, 45 Fig. 1; and Fig. 4, a detail perspective view of the drum.

A practical embodiment of the invention is disclosed in the accompanying drawings, forming a part of this specification in which 50 similar numerals of reference indicate corresponding parts throughout the several views.

The tank 1 may be of any usual construction and contains the coating in a liquid 55 form. A pair of spaced rails 2 are located

through the tank and extend downwardly as shown at 3 from the feed end of the tank to the longitudinal center of the tank as shown at 4 and then upwardly at a steeper incline as shown at 5 to a point 6 above the 60 farther end of the tank, the delivery ends of the rails terminating in downwardly inclined portions 7.

A toothed track 8, of the same shape as the rails 2 is connected upon the inner side 65 of each rail. As will be hereinafter described the drums which contain the plates or other articles to be coated are provided with toothed wheels which ride upon the tracks 8, the axles of the drum riding upon 70 the rails 2.

Each drum comprises the circular heads 9, each provided with a concentric outwardly protruding axle 10 arranged to ride upon the rails 2, a toothed wheel 11 being mounted 75 upon the outer end of each axle and arranged to engage the toothed tracks 8.

The heads 9 are connected together by the spaced cross bars 12 each of the cross bars being provided with spaced lugs 13 upon its 80 inner face forming a rack within to receive the plates as shown at "A" in Figs. 2 and 3.

One of these cross bars designated by the numeral 14 is hinged at one end to one of the heads 9 as shown at 15, the other end being provided with a suitable catch 16 by means of which it is detachably secured to the other head. By this construction the catch 16 may be released and the bar 14 swung outwardly upon its hinge to permit 90 plates or the like being placed within the drum or removed therefrom.

The rear or delivery ends of the rails 2 and tracks 8 are supported by the uprights 17 which extend upwardly from the rear 95 end of the tank 1. An upper rail 18 is spaced above and parallel with the upwardly extending portion 5 of each of the rails 2, said upper rails being supported at their rear extremities by the side walls of the 100 tank and at their upper extremities by the uprights 17. Each of these upper rails is curved at its lower end as shown at 19 and at its upper end as shown at 20 and they are spaced a sufficient distance from the portions 5 of the lower rails to form a guide slot 21, through which the axles 10 of the drum extend.

Bearings 22 are mounted near the upper ends of the rails 18 on the upper sides 110

thereof and a shaft 23 is journaled in said bearings, a crank 24 or other suitable means for rotating said shaft being provided thereon. A pair of spaced sprocket wheels 25 are fixed upon the shaft 23 at points slightly spaced from the inner faces of the rails. A shaft 26 is journaled in suitable bearings 27 located near the lower extremities of the rails 18 and a pair of spaced sprockets 28 10 similar to the sprockets 25 and alined therewith are fixed upon the shaft 26. An endless chain 29 is located around each alined pair of sprockets 25 and 28, each of said chains being provided at intervals with 15 hooks 30 as best shown in Fig. 1 of the drawings.

The operation of the device is as follows: The hinged cross bar 14 is swung outwardly from the drum as above described and the 20 plates "A" or other articles to be coated are placed within the drum after which the hinged arm is moved back into the closed position and the catch 16 fastened.

The drum is then placed at the upper or 25 feed end of the portions 3 of the rails 2, the toothed wheels 11 thereon engaging the teeth upon the track 8. The drum will then be carried by gravity down the inclined portions 3 of the rails and tracks into the 30 tank, immersing the plates therein in the liquid coating. The endless chains 29 will be rotated in the direction of the arrow in Fig. 1 and as the drum reaches the point 4 upon the rails the hooks 30 will engage the 35 axles 10 of the drum, carrying it up the inclined portions 5 of the rails, the toothed wheels 11 upon the drum by their engagement with the toothed track causing the drum to rotate forwardly as it moves upwardly out of the tank. This rotation of 40 the drum through the tank and upon the track leading from the tank will cause the liquid coating to be spread evenly over the entire surface of each plate and will cause 45 any surplus liquid coating upon the plates to be removed by centrifugal action. As the drum reaches the upper end of the inclined portions 5 of the rails it will be guided on to the downwardly inclined portions 50 7 of the rails by the curved portions 20 of the guide slot, the drum rolling down these inclined delivery ends of the rails from which it is removed and opened and the 55 coated plates removed therefrom, and again placed in a kiln in the usual manner to burn the glaze upon the plates.

With this construction of coating device a large number of plates may be quickly and properly coated in a short time as the 60 drums may be quickly filled and passed through the device with a minimum of labor.

It will be understood that although the device is described as being especially designed for use in coating china and porce-

lain ware with a glazed coating, that it is adaptable to use for various forms of coating articles with a liquid coating.

I claim:—

1. A liquid coating device, including a 70 tank containing liquid, a drum containing articles to be coated and means for passing said drum through the tank and rotating the drum as it is passed through the tank.

2. A liquid coating device, including a tank containing liquid, rails extending through said tank, a drum containing articles to be coated and means for passing said drum over said rails and rotating the 80 drum upon the rails.

3. A liquid coating device, including a tank containing liquid, toothed tracks extending through said tank, a drum containing articles to be coated, toothed wheels 85 upon said drum arranged to engage the toothed tracks and means for passing the drum over said tracks.

4. A liquid coating device, including a tank containing liquid, rails extending downwardly into the tank and upwardly out of the tank, a drum containing articles to be coated and arranged to be moved downwardly upon said inclined rails into the tank and means for carrying the drum up the 95 inclined rails out of the tank.

5. A liquid coating device, including a tank containing liquid, rails extending downwardly into the tank and upwardly out of the tank, a drum containing articles to 100 be coated and arranged to be moved downwardly upon said inclined rails into the tank, means for carrying the drum up the inclined rails out of the tank, and means for rotating the drum upon said rails.

6. A liquid coating device, including a tank containing liquid, toothed tracks inclined downwardly into the tank upon one side and upwardly out of the tank on the opposite side, a drum containing the articles 110 to be coated, toothed wheels upon said drum for engaging the toothed tracks, said drum arranged to be rolled down said inclined tracks into the tank and means for moving the drum up the inclined tracks out of the 115 tank.

7. A liquid coating device, including a tank containing liquid, rails inclined downwardly into the tank upon one side and upwardly out of the tank upon the opposite side, a drum containing articles to be coated and arranged to be rolled down the inclined portions of the rails into the tank, an endless chain located adjacent said upwardly inclined portions of the rails and means upon said chain for engaging the drum and rotating it upwardly upon said inclined rails out of the tank.

8. A liquid coating device, including a tank containing liquid, rails inclined down- 130

- wardly into the tank upon one side and upwardly out of the tank on the opposite side, a drum containing articles to be coated and arranged to be rolled down the inclined portions of the rails into the tank, axles upon said drum and means adjacent the upwardly inclined portions of the rails for engaging said axles and rotating the drum upwardly upon said inclined rails out of the tank.
9. A liquid coating device, including a tank containing liquid, rails inclined downwardly into the tank upon one side and upwardly out of the tank upon the opposite side, a drum containing articles to be coated and arranged to be rolled down the inclined portions of the rails into the tank, axles upon said drum engaging said rails, upwardly inclined guide rails spaced from the upwardly inclined portions of the said first named rails and means for moving the drum upwardly upon said inclined portions of the rails out of the tank.
10. A liquid coating device, including a tank containing liquid, rails inclined downwardly into the tank upon one side and upwardly out of the tank upon the opposite side, a drum containing articles to be coated and arranged to be rolled down the inclined portions of the rails into the tank, axles upon said drum engaging said rails, upwardly inclined guide rails spaced from the upwardly inclined portions of the said first named rails, an endless chain located adjacent said upwardly inclined portions of the rails and means upon said chain for engaging the drum and rotating it upwardly upon said inclined rails out of the tank.
11. A liquid coating device, including a tank containing liquid, rails inclined downwardly into the tank upon one side and upwardly out of the tank upon the opposite side, a drum containing articles to be coated and arranged to be rolled down the inclined portions of the rails into the tank, axles upon said drum engaging said rails, upwardly inclined guide rails spaced from the upwardly inclined portions of the said first named rails, an endless chain located adjacent said upwardly inclined portions of the rails and means upon said chain for engaging the drum and rotating it upwardly upon said inclined rails out of the tank.
12. A drum for coating articles with liquid, comprising circular heads, spaced cross bars connecting said heads and a toothed wheel concentrically mounted upon each head.

In testimony that I claim the above, I have hereunto subscribed my name.

FRANK H. SEBRING, Jr.
